UNITED STATES PATENT OFFICE.

ASA E. REED, OF SAN BERNARDINO, CALIFORNIA.

CIRCULAR TYPE OF POWER GENERATOR.

Application filed March 21, 1921. Serial No. 454,146.

To all whom it may concern:

Be it known that I, ASA E. REED, a citizen of the United States, residing at San Bernardino, in the county of San Bernardino 5 and State of California, have invented new and useful Improvements in Circular Type of Power Generators, of which the following is a specification.

This invention relates to improvements in 10 power generators adapted to be operated by air or water currents or by waves and tides.

The principal object of the invention is 15 to produce an apparatus which will be caused to move in one direction regardless of the direction of the propelling current or force so that a change of direction of the propelling force will not result in a reversal of the apparatus. Thus it is not 20 necessary to provide complicated reversing mechanism for the apparatus as is usually employed in devices of this nature, so that a more simple and economical apparatus is obtained.

25 Another object of the invention is to provide auxiliary means for causing the propelling force to move the apparatus.

This invention also consists in certain 30 other features of construction and in the combination and arrangement of the several parts, to be hereinafter fully described, illustrated in the accompanying drawings and specifically pointed out in the appended claims.

35 In describing my invention in detail, reference will be had to the accompanying drawings wherein like characters denote like or corresponding parts throughout the several views, and in which:—

40 Figure 1 is a side view of an apparatus constructed in accordance with my invention.

Figure 2 is a section on line 2—2 of Figure 1.

45 Figure 3 is an enlarged view of the rotary member or wheel with parts broken away.

Figures 4, 5 and 6 are detail views.

As shown in these views 1 indicates a supporting frame which is secured to a base 2.

50 A shaft 3 is rotatably mounted in the frame and this shaft carries the wheel or rotatable member 4. This member is formed of the ring 5, the hub 6 and the spokes 7, the wheel being braced by the bars 8 which extend from the rim to the collars 9 on the shaft.

55 Blades 10 are hinged to each spoke and these

blades occupy the spaces between the spokes as shown. The edges of the blades may be reinforced by the strips 11. In order to limit the swinging movement of the blades 60 I provide the arms 12 which project outwardly from the rim and have adjustably secured thereto the angle stop plates 13, which project inwardly into the path of the blades so as to be struck by the blades. As 65 shown in the drawings the arms 12 are of angle shape with their centers connected with the rim so that the stop plates will hold the blades in an inclined position relative to the plane of the wheel or rotary member 70 and at either side thereof.

It will thus be seen that when the current of air, water or the like strikes the blades it will swing them in one direction or the other until they strike the stop plates when 75 further movement of the blades will be prevented and the pressure of the current against said blades will cause the wheel to rotate. If the direction of the current should be changed the blades would simply 80 reverse so that pressure will be applied to the sides of the blades and thus the member would continue to rotate in the same direction.

By having the angle plates 13 adjustably 85 mounted on the arms 12 the degree of movement of the blades can be adjusted to suit conditions.

I also place flanges or fins 14 on the sides 90 of the blades, these flanges being concentric with the rim and act to assist in imparting a rotary movement to the member by the current. These flanges will be acted on by the current when the blade has been reversed, the blades tending to dam the current when reversed and thus cause the current to act on the flanges. 95

It will be understood that the device is to be placed in a position with its axis in the plane of the path of the current so that the 100 current will act on all the blades to incline them to the far side of the rotary member and the pressure exerted on said inclined blades will thus cause the member to revolve. If the current should be reversed and flow 105 from the opposite direction the blades would swing on the hinges towards the other side of the member and thus still be acted upon by the current and drive the member in the same direction as before. 110

The device may be used as a wind wheel, a water motor or a wave or tide motor.

When used as a water motor it is preferably completely submerged.

It will of course be understood that any number of these rotary members may be used on the same shaft or on separate shafts and the power may be transmitted from the shaft or shafts or from the members themselves in any desired manner.

If desired the blades may be corrugated, 10 the corrugations being concentric with the axis and acting to assist the flanges when imparting a rotary movement to the member.

If the current should flow in a path parallel to the plane of the rotary member it would exert pressure upon some of the blades while those blades which have their hinged edges acted upon by the current will swing into the plane of the path of the current 20 and thus offer but slight resistance to the rotary movement of the member. In this case, however, only a portion of the blades have pressure exerted upon them by the current so that the full power of the current is not 25 utilized as is the case where the current flows against one side of the member. In both cases, however, the member will continue to rotate in the same direction even though the direction in which the current is 30 flowing is reversed.

It is thought from the foregoing description that the advantages and novel features of my invention will be readily apparent.

I desire it to be understood that I may 35 make changes in the construction and in the combination and arrangement of the several parts, provided that such changes fall within the scope of the appended claims.

What I claim is:—

40 1. An apparatus of the class described comprising a base, a supporting frame se-

cured to said base, a rotatable shaft mounted in said frame, a rotatable member carried by said shaft, said member consisting of a frame, a hub and spokes bars adapted to embrace in said rotatable member, collars provided on said shaft and said bars extending from the rim of the rotatable member to said collars, blades hinged to said spokes and occupying space therebetween, reinforcing strips provided on the edge of said blades, arms projecting outwardly from the rim of said rotatable member to limit the swinging movement of said blades, angle stop plates adjustably secured to said arms which project inwardly into the path of the blades so as to be struck by the latter and flanges divided on the sides of said blades which are concentric with the rim and act in imparting a rotary movement to the member by the current.

2. An apparatus of the class described comprising a base, a supporting frame secured thereto, a rotatable shaft mounted in said frame and a rotatable member carried thereby, said member including a ring, hub and spokes, collars provided on said shaft, bars extending from the rim to the collars which are adapted to support said rotatable member, blades hinged to each spoke and adapted to occupy spaces between the spokes, strips adapted to reinforce the edges of the blades, arms projecting outwardly from the rim to limit the swinging movement of the blades, angle stop plates secured to said arms which project inwardly into the path of the blades, flanges provided on the side of the blades which are concentric with the rim for imparting a rotary movement to said rotatable member.

In testimony whereof I affix my signature:
ASA E. REED.
